UNITED STATES PATENT OFFICE.

ADOLPH F. BREWER, OF SAN FRANCISCO, CALIFORNIA.

GAGE FOR GRINDING TWIST OR FLAT DRILLS.

SPECIFICATION forming part of Letters Patent No. 403,175, dated May 14, 1889.

Application filed August 15, 1888. Serial No. 282,820. (No model.)

To all whom it may concern:

Be it known that I, ADOLPH F. BREWER, a citizen of the United States, residing in the city and county of San Francisco, and State of California, have invented a new and useful Improvement in Adjustable Standard Bevel-Gages for Grinding Twist-Drills, of which the following is a specification.

This invention relates to gages for grinding-drills, and the novelty will be fully understood from the following description and claims, when taken in connection with the annexed drawings, in which—

Figure 1 is a front view of my improved device. Fig. 2 is a side elevation of the same, showing it applied to a twist-drill. Fig. 3 is a plan view with the drill in position. Fig. 4 is a vertical central sectional view with the drill removed, and Fig. 5 is a perspective view 20 of the slide for adjusting the gage rule or arm.

Referring by letter to the said drawings, A indicates the box-square, which may be of the form usually employed, being adapted to receive within its walls a drill to be operated 25 upon. This box-square, which is of an angular form, is provided at its upper end and at the angle of the wings or walls with a transversely-arranged box, H, which is designed to serve as a guide for a slide, as will be presently explained. The box H is provided with a transverse slot, a, and the walls at each side of this slot are provided with shoulders or flanges b.

E indicates an adjusting-screw, which is arranged in the box H, and has a bearing in one end thereof, as shown.

d indicates an adjusting-slide for the gage rule or arm. This slide d is of a form substantially as shown in Fig. 5 of the drawings, 40 having a square portion, e, provided with an internally-threaded aperture to receive the threaded rod or screw E. It is furthermore provided with a reduced rectangular portion, f, which travels in the slot a of the box H, and receives a correspondingly-shaped aperture in the gage rule or arm B, and a threaded extension, g, to receive a wing-nut, h, whereby the slide and arm may be secured in position with respect to the box-square. It will 50 thus be seen that by manipulating the screw E the slide and gage rule or arm B may be

moved to the desired point, and by means of the wing-nut h the whole fixed to the box-square.

When the wing-nut has been loosened on 55 the threaded extension of the slide, the latter, together with the gage-rule, may be moved to the desired point across the box H.

The upper end of the box-square or the guide-box H is beveled, as shown at I. This 60 bevel may be on any desired angle, but preferably on an angle of about fifty-nine degrees, and the gage rule or arm B is designed to have a bearing on this beveled surface.

The gage-rule B has its inner end formed 65 as shown, so as to bear upon the guide-box, and is provided with an aperture to receive the reduced square portion of the slide d. From this apertured portion of the gage-rule extends an oblique branch which is slotted. 70 Arranged in the slotted portion of the branch is a threaded rod, i, which is provided at its outer end with a head, J, whereby it may be manipulated.

F indicates a guide-mortise or pointer, which 75 is provided with an internally-threaded aperture to receive said screw or rod i, and is adapted to travel in the slot of the arm when the rod has been turned.

In operation I place the box-square upon a 80 drill, as shown in Fig. 2. If the drill is small, the cutting-edges are in lines close to the center; but in large drills they are off the center. The drill is then ground to the desired point.

Having described my invention, what I claim 85 is—

1. The combination, with the box-square and gage-rule, of a guide-box formed thereon and provided with a bevel, as described, and adapted to serve in sustaining the gage-rule, 90 substantially as specified.

2. The combination, with a box-square provided with a guide-box beveled as described, of a slide arranged in said guide-box, a gage-rule connected with said slide, and a set-screw 95 for adjusting the slide and rule, substantially as specified.

3. The combination, with a box-square, of a gage-rule connected therewith, and a screw for laterally adjusting the rule with relation to 100 the square, substantially as specified.

4. The combination, with the gage-square

provided with the guide-box beveled as described, of the slide arranged in said box and having an internally-threaded aperture, a reduced rectangular portion and a reduced 5 threaded portion, a set-screw journaled in the guide-box and engaging the threads in the slide, the gage-rule having an aperture to receive the reduced rectangular portion of the

slide, and a wing-nut to receive the reduced threaded portion of said slide, substantially as specified.

ADOLPH F. BREWER.
